UNITED STATES PATENT OFFICE.

WALTER RUSSELL SIEG, OF WATERLOO, IOWA, ASSIGNOR TO WATERLOO CEMENT MACHINERY CORPORATION, OF WATERLOO, IOWA, A CORPORATION OF IOWA.

BACK-FILLING MACHINE.

1,264,693.

Specification of Letters Patent. Patented Apr. 30, 1918.

Application filed October 2, 1915. Serial No. 53,744.

To all whom it may concern:

Be it known that I, WALTER RUSSELL SIEG, a citizen of the United States, residing at Waterloo, in the county of Blackhawk and 5 State of Iowa, have invented certain new and useful Improvements in Back-Filling Machines, of which the following is a description.

My invention belongs to that general class 10 of devices known as back filling machines, and relates particularly to that class of devices for filling trenches and excavations. It is particularly desirable that a machine of this kind shall be as light as possible, so 15 as to insure portability, but at the same time to be strong and rigid in order to withstand the hard usage usually given a machine of this class. It is particularly desirable also that the machine be capable of filling a con- 20 siderable amount of trench, ditch, or excavation without moving the machine along, and yet pull the scraper from the straight true line upon which the cables are wound. The invention has among its objects the pro- 25 duction of a machine of the kind described that will possess the advantages referred to, and that shall be simple, convenient, durable, efficient, and satisfactory in use, and not likely to turn turtle or easily get out of 30 order. Further objects and advantages in the device will be obvious to those skilled in the art from the disclosure hereinafter given.

To this end my invention consists in the novel construction, arrangement and combi- 35 nation of parts herein shown and described, and more particularly pointed out in the claim.

In the drawings, wherein like reference characters indicate like or corresponding 40 parts,

Figure 1 is a side elevation of the preferred form of the device;

Fig. 2 is a plan view of a portion of the same, illustrating the moving of the machine 45 by its own power;

Fig. 3 is a top plan view of the machine, and

Fig. 4 is a sectional view taken substantially on line 4, 4 of Fig. 1.

Referring to the drawings, 1, 1 represent 50 suitable skids mounted on trucks, consisting of the axles 2 and wheels 3 at the rear, and the front axle 4 and wheels 5 at the forward end. The forward ends of the skids are con- 55 nected by the part 6 and pivoted to the axle,

so that the front wheels and axle may be turned to steer the device. As shown, the axle part 4 is pivotally secured to the part 6 at 6', the skids or frame being strengthened and braced by the parts 8 and 9, or 60 their equivalents for the purpose, the whole forming a main frame. The truck may also be provided with a tongue 7 of any suitable construction, by means of which the front wheels may be turned to steer the device, or 65 the truck may be drawn ahead. The frame is preferably underslung, as shown, so as to lower the center of gravity, and make the device less liable to overturn. Mounted on the skids is what may be termed a turntable 70 base part 10, which carries a coöperating turntable part 11, the same being pivotally secured in place by a bolt 12, or equivalent means for the purpose. The turntable parts 10 and 11 are preferably of considerable area 75 and carry skids 15, 15, which may be suitably connected and braced by the cross parts 16, forming a second or auxiliary frame. As shown, the skids 15 are secured to and carried by the turntable part 11, so that the 80 same may be turned at any desired angle. Mounted on the skids 15 is a suitable source of power, as for example, a gas engine, electric motor, or the like, which is arranged to drive a suitable drum. As shown, bearing 85 members 16' are carried by each skid, the same carrying a shaft 18, upon which is mounted a drum 17, suitable means being provided for operatively connecting the shaft and drum. As shown, I provide a 90 clutch 19, arranged to be controlled by rod 31, and handle or lever 32, it being understood, however, that any type of clutch mechanism may be employed, and hence I have not shown the same in detail. I have 95 illustrated a gas engine 23, 22 being the crank shaft of the same and 24 the usual fly wheels. Power may be transmitted from the gas engine or source of power by a sprocket chain 21 running over the sprocket 100 wheel 20, or in an equivalent manner. The drum is shown provided with the usual brake band 25, controlled by a part 26, which may be connected through a bell-crank 27, 28 and rod 29, to a controlling lever 30. 105 Carried by the frame or skids is a frame 33, 34, which carries a pair of spaced rollers 35 (see Figs. 3 and 4). These rollers are adapted to guide the cable on to the drum, or rather maintain the drum in the line of 110

a direct pull, that is to say if the man with the scraper goes to one side, so there is not a direct pull on the drum, the cable will bear against one of the rollers and swing the skid 5 on its turntable until the drum is in proper alinement with the direction of pull.

The drum shaft 18 is provided with a nigger head 37, from which may pass a cable 38. As shown, 40 is a bracket provided with a sheave 39, over which the cable 38 extends in moving the machine. The turntable 11 is provided with one or more holes 14', and the part 10 has similarly formed holes 14, so that a pin 13 may be 15 passed through the holes in alinement, thereby locking the movable skids in the desired position. This is particularly desired when moving the machine, as the skids 16 carrying the sheave 39 may be locked in 20 the position shown in Fig. 2. To move the machine a sheave 43, or the equivalent, is secured to a tree, post, or a stake 44 driven in the ground, and the cable 38 passed over the same, but connected to the end of the 25 tongue, the opposite end being snubbed around the nigger head. As is obvious, when the turntable is locked in position and the cable snubbed around the nigger head, the machine can be moved ahead until 30 it is in the desired location, when the cable is taken off the nigger head. By attaching the cable to the tongue the machine is guided without the help of an extra man.

Any type of scraper may be used with 35 this machine, preferably one of the flat type of well known construction, as it will push a considerably more dirt than the ordinary slip scraper. In operation the machine is placed upon one side of the ditch or trench 40 and the scraper on the other, the drawing cable 36 being attached to the scraper and extended over the drum. The scraper is drawn to the trench, pushing the dirt therein, then the scraper may be carried 45 back for another load, the brakes being released so that the drum can run free. The skids being mounted on a turntable, allows the operator to fill a vast amount of trench with the machine standing in one position. 50 It will be noted, as previously mentioned, that the main skids 1 are hung below the axles, so that the machine has a low center of gravity and cannot be easily overturned. With a machine of this type the machine 55 may be controlled or moved forward by one

man. The nigger head, while desirable for moving the machine ahead, may be used in driving and pulling piles, and many other similar jobs required around ditch or trenching work. As is obvious, if the auxiliary or pivoted skids or frame are locked in the position shown in Fig. 1, the machine may be moved ahead as desired without passing the rope over the pulley or sheave 39. 60

Having thus described my invention, it 65 is obvious that various immaterial modifications may be made in the same without departing from the spirit of my invention; hence I do not wish to be understood as 70 limiting myself to the exact form, construction, arrangement and combination of parts herein shown and described, or uses mentioned.

What I claim as new and desire to secure 75 by Letters Patent is:—

The combination in a back filling machine of the kind described of a main frame having supporting wheels therefor arranged at the rear end and supporting wheels arranged at the front end and pivotally connected therewith, a turn-table part arranged on said frame, a coöperating turn-table part rotatably mounted on said first part, an auxiliary frame carried by said coöperating turn-table part, said auxiliary frame provided with a drum projecting at one side thereof, a sheave carried by said auxiliary frame at one side adjacent said projecting drum part, said sheave disposed substantially in a line and extending transversely 90 the auxiliary frame at the center of pivotal connection of said rotatable turn-table part, whereby when said part is rotated the sheave may be brought substantially in alinement with the center line of the main 95 frame, a second sheave provided with means for securing the same to a fixed part in advance of the machine, and a cable extended about said drum and through said first mentioned sheave and thence through the second mentioned sheave, and operatively connected with said front wheels. 100

In testimony whereof, I have hereunto signed my name in the presence of two subscribing witnesses.

WALTER RUSSELL SIEG.
